UNITED STATES PATENT OFFICE.

ROBERT A. MENEFEE, OF ALBRIGHT, WEST VIRGINIA.

DEVICE FOR HANDLING AND SCALDING HOGS.

No. 856,893.

Specification of Letters Patent.

Patented June 11, 1907.

Application filed February 23, 1907. Serial No. 358,915.

To all whom it may concern:

Be it known that I, ROBERT A. MENEFEE, a citizen of the United States, residing at Albright, in the county of Preston and State of West Virginia, have invented a new and useful Device for Handling and Scalding Hogs, of which the following is a specification.

This invention has relation to devices for handling and scalding hogs and it consists in the novel construction and arrangement of its parts as hereinafter shown and described.

The object of the invention is to provide a means whereby heavy hogs may be easily and readily lifted and handled at the time that they are slaughtered and when scalded and when carried away from the scalding tank to be dressed.

The device consists primarily of a tank above which is erected a frame. A cradle is arranged to move vertically within the frame and enter the said tank. A windlass is mounted upon the frame and ropes wind about said windlass and pass over elevated pulleys and connect with the cradle. The frame is so constructed that it may be easily and readily detached from the tank. An elevated flat section is connected with said frame and at points beyond the frame is supported by collapsible supports. Thus when the device is not in use the parts may be easily and readily separated or knocked down and will require but little room for storage purposes.

In the accompanying drawing:—Figure 1 is a side elevation of the device. Fig. 2 is a top plan view of the same, and Fig. 3 is an end view of the same.

The apparatus consists of the tank 1 which is preferably oblong in horizontal section. The said tank is provided upon the outer surfaces of its ends with the pockets 2. The lower ends of the uprights 3 fit in said pockets and the said uprights form portions of a frame which is located over the tank. The tank is provided with a suitable lining 4 and the guides 5 are attached to the uprights 3 and pass down into the tank. The windlass 6 is attached to one of the uprights 3 and the ropes 7 wind upon said windlass. Said ropes pass over the elevated pulleys 8, 8 and are attached at their ends to the bails 9. Said bails in turn being attached to the ends of the parallel bars 10 which form the base of the cradle 11. The said bars 10 are connected together by the cross bars 12 which are slightly concaved along their upper edges.

The upper ends of the uprights 3 are connected together by the beam 13 and one end of the track 14 is pivoted to said beam 13. Said track is provided at suitable intervals with the supports 15 which are collapsible and consist of the side pieces 16 pivotally joined together near their upper ends as at 17 and having at their upper ends sockets 18 for the reception of the said track 14. The lower brace 19 is made up of sections hinged together as at 20 and pivotally connected as at 21 at their ends with the said side pieces 16.

The apparatus is used as follows:—The tank 1 is filled with water and the cradle 11 is lowered into the same. Hot rock or iron is then thrown into the water and rests upon the said cradle. When the water has become heated the cradle 11 is elevated by turning the windlass 6 and the rock and iron is lifted out of the tank. The material is then removed from the cradle. The hog is then run along the track 14, the animal previously having been butchered and is placed upon the cradle 11. The said cradle is then lowered into the tank. The animal is thoroughly scalded after which the cradle is elevated as above described. A gambrel stick is applied to the hind leg of the animal and it is run off on the track 14 for dressing.

It will be observed that the uprights 3 may be readily separated from the tank 1 and that the beam 13 may be disconnected from said uprights. Thus the parts may be knocked down when not in use and stored away. As the track support is made up of sections and members pivotally connected together it may also be collapsed and will occupy but small space.

Having described my invention what I claim as new and desire to secure by Letters Patent is:—

1. An apparatus of the character indicated comprising a tank, pockets attached to said tank, uprights fitting in said pockets guides mounted upon the uprights, a windlass attached to one of the uprights, a beam connecting the upper ends of the uprights together, a cradle mounted for movement along the guides, pulleys journaled above the cradle and ropes attached to the cradle and the windlass and passing over said pulleys.

2. An apparatus of the character indicated comprising a tank, pockets attached to said tank, uprights fitting in said pockets, guides mounted upon the uprights, a windlass attached to one of the uprights, a beam con-

necting the upper ends of the uprights together, a cradle mounted for movement along the guides and having bars which receive the said guides between their ends, pulleys journaled above the cradle and ropes attached to the cradle and the windlass and passing over said pulleys.

In testimony that I claim the foregoing as my own, I have hereto affixed my signature in the presence of two witnesses.

ROBERT A. MENESEE.
